UNITED STATES PATENT OFFICE.

BERNARD HAUSMANN, OF SAN FRANCISCO, CALIFORNIA.

COMBINED SLIDABLE AND SWINGING SASH.

SPECIFICATION forming part of Letters Patent No. 613,512, dated November 1, 1898.

Application filed February 25, 1898. Serial No. 671,558. (No model.)

To all whom it may concern:

Be it known that I, BERNARD HAUSMANN, a citizen of the United States, residing in the city and county of San Francisco, State of California, have invented an Improvement in a Combined Slidable and Swinging Window-Sash; and I hereby declare the following to be a full, clear, and exact description of the same.

My invention relates to a mechanism for sliding window-sashes whereby they can be easily disengaged, so as to turn about hinges and swing inwardly for the purpose of obtaining access to the outside of the sash.

It also comprises details of construction, which will be more fully explained by reference to the accompanying drawings, in which—

Figure 1 is an interior view of my window. Fig. 2 is a face view of the pulley-stile, showing the chain-locking device. Fig. 3 is a vertical section on line $y-y$ of Fig. 4. Fig. 4 is a horizontal section of my window on line $x-x$ of Fig. 3.

The object of my invention is to provide a means for conveniently obtaining access to the exterior surfaces of windows.

In large heavy plate-glass windows, which are frequently more than five feet in width and each sash more than four feet in height, the weight of glass and sash will approximate one hundred pounds, and in the present construction of lofty buildings of from eighteen stories upward the danger and difficulty in attempting to clean the outside of such windows are apparent.

In my invention I have designed such a combination of the sliding and hinged sash that when the sash is used in the usual manner, sliding vertically, it is perfectly counterbalanced and operates in the manner usual to this class of sash. When it is desired to open it inwardly, the counterbalance-weight upon one side is automatically disengaged and latched, thus allowing the sash to be immediately swung on the hinges by which the opposite stile is fixed.

In the drawings, A represents the pulley-stiles; B, the parting-strips between which the upper and lower sashes slide. The weights by which the sash is counterbalanced are here shown as suspended from chains D, which pass over the usual pulleys at the top, and extend-

ing down in the channel between the stops and parting-strips. The lower end of the chain is fixed to the detachable sliding sash-stile E. 55 This stile is in the form of a strip of wood having a width equal to the thickness of the sash-stile proper and a thickness a little more than equal to the depth of the stop by which it is held in place, so that when the sash is 60 disengaged from this strip it may swing clear of the stop without contact. The chain D is permanently fixed to the sliding strip E at a suitable point between the top and the bottom. Above this point of attachment a short 65 bar F passes through or is fixed to the chain, lying in a transverse groove made in the slide E, so that when the sash G is in its normal position one edge of the sash will be hinged to the slide E' by hinges, (shown at H,) while 70 the opposite edge will be locked to the slide E as follows:

In the edge of the sash G are fixed the hook-bolts I, the shanks of which are parallel with and stand out a short distance from the edge 75 of the sash. These hook-bolts normally drop into locking-loops J, which are fixed upon the adjacent faces of the slides E and the edges of the sash, and the slide is thus locked into a single structure. As the weight-chains are 80 connected with the outer faces of these slides it will be manifest that the counterweight always pulling upward will cause the two to remain in engagement and slide up and down together. 85

When it is desired to open or swing the sash on its hinges H, a link of the chain is pushed into an open slot K, formed in a plate L, which is permanently fixed in the channel in which the sash and slide move and with the slot approximately a little out of the line of the ordinary travel of the chain. The chain normally travels just in front of this plate L; but when, as before stated, it is desired to disengage the sash from this slide E the chain is 95 pressed into the slot K and then moved to one side under the lip K' of this slot, so that when the sash is again raised it and the slide still move up until the transverse bar F, before described as being fixed to the chain, strikes the under part of the socket-plate L, where it is stopped, and the chain and slide are thus prevented from further movement. By then lifting slightly upon the sash the hook-bolts I 100

are disengaged from the loops J, with which they have been hitherto connected, and the sash is then free to swing away from the slide E on the hinges H. These hinges being on the 5 inner faces of the sash, either concealed or visible, as may be desired, it will be manifest that the sash will turn inwardly, and the face of the glass will then be exposed for cleaning or other purposes.

- 10 To prevent the strip to which the sash is hinged from being pulled out of its place by the weight of the swinging sash, I have shown the strip channeled on both edges, and both the stops and parting-strip, between which it 15 slides, have tongues O, which project into the grooves or channels, and thus hold it in place while the sash is swung inward, but will allow it to slide up and down freely when the two are locked together.
- 20 Both sashes can be operated in the same manner. The lower one being first opened inwardly, the upper one can be pulled down to near the bottom of the window-opening, and the same operation being effected it can also 25 be opened inwardly, leaving both sashes fully exposed inside of the room.

When the sashes are to be again placed in their normal position, they are first closed, with the swinging edges in line with the slides 30 E and the hook-bolts I in line above the loops to which they are engageable. The sash then dropping down, either because the single counterweight upon the hinge side is not sufficient to quite balance it or by pulling a little, if 35 necessary, the hook-bolts will engage the loops in the slides E. The sash is then pulled down sufficiently to disengage the bar F from the stop-plate L, and when it has been withdrawn far enough from the lower edge of this plate 40 the chain can be pushed out of the groove in the plate in which it lies and then drawn out through the channel K, so that it assumes its normal position in the channel in which the sash is movable. The parts are then slidable 45 vertically in the usual manner.

In order to make a tight joint where the sashes close against the sliding strips, I have shown coincident channels and projecting tongues, as at M M', which fit together when 50 the sashes are closed, and thus prevent any water which may beat in passing through the joint between the two. These channels and tongues are so disposed with relation to each other that they easily separate when the 55 sashes are to be swung open.

Having thus described my invention, what I claim as new, and desire to secure by Letters Patent, is—

1. In a window-sash, the combination of 6c sliding strips channeled on both edges, parting-strips having tongues adapted to engage one of said channeled edges and stops adapted to engage the opposite channeled edge, a sash, one edge of which is hinged to one of said strips, a locking-loop fixed to the opposite 65 strip and a hook-bolt fixed in the edge of the sash and with its shanks parallel with and separated from said edge, and adapted to interlock with said loop, and counterbalance-weights, the chains of which are fixed to the 7c outer faces of the slideable strips, whereby the window is counterbalanced and the parts are slidable in unison.

2. In a window-sash of the character described, strips slideable in the vertical grooves 75 or channels at the sides of the window-frame, a sash one edge of which is hinged to one of said strips, the other edge provided with hook-bolts adapted to engage with corresponding loops in the corresponding strip, counter- 80 weight-chains connecting with the exterior faces of the strips whereby the windows are counterbalanced and slideable, a stop-bar fixed upon one chain, and a plate fixed in the channel in which the strip slides and adapted to 85 be engaged by the stop-bar, whereby the strip is arrested and the sash allowed to be lifted and the hook-bolts disengaged preparatory to opening the sash.

3. In a window-sash of the character de- 90 scribed, strips slideable in grooves or channels at the sides of the window-frame, a sash, one edge of which is hinged to the adjacent strip, grooves formed in both of the edges of the strip and tongues projecting inwardly from 95 the stops and from opposite sides of the parting-strip into said grooves whereby the slideable strip is retained in place, and a means comprising a loop on the strip and a hook on the sash with its shank parallel with and sepa- 100 rated from the edge thereof for interlocking or disengaging the opposite edge of the sash with the corresponding independent slideable strip.

In witness whereof I have hereunto set my 10 hand.

BERNARD HAUSMANN.
